UNITED STATES PATENT OFFICE

167,492

WINDOW VALANCE OR SIMILAR ARTICLE

Victor Zakarin, New York, N. Y.

Application December 23, 1949, Serial No. 6,819

Term of patent 14 years

(Cl. D21—6)

To all whom it may concern:

Be it known that Victor Zakarin, a citizen of the United States of America and resident of the Borough of Manhattan, city and State of New York, has invented a new, original, and ornamental Design for Window Valance or Similar Article, of which the following is a specification, reference being had to the accompanying drawing, forming part thereof, in which:

Fig. 1 is a front elevational view of a window valance or similar article, showing my new design;

Fig. 2 is a rear elevational view thereof; and

Fig. 3 is a cross-sectional view taken substantially along the line 3—3 of Fig. 1.

Figs. 1 and 2 are partially broken away for convenience in illustration, the unit being repeated in the omitted portion the same as in the portions shown.

The dotted lines appearing in Fig. 2 of the drawing represent lines of stitching.

I claim:

The ornamental design for a window valance or similar article, substantially as shown and described.

VICTOR ZAKARIN.
